UNITED STATES PATENT OFFICE.

WILLIAM H. TALLMAN, OF AMSTERDAM, NEW YORK.

IMPROVEMENT IN SOLDERING-LAMPS.

Specification forming part of Letters Patent No. 118,653, dated August 29, 1871; antedated August 18, 1871.

To all whom it may concern:

Be it known that I, WILLIAM H. TALLMAN, of Amsterdam, in the county of Montgomery and in the State of New York, have invented certain new and useful Improvements in Jewelers' Soldering-Lamp; and do hereby declare that the following is a full, clear, and exact description thereof, reference being had to the accompanying drawing and to the letters of reference marked thereon making a part of this specification.

The nature of my invention consists in the construction and arrangement of a jewelers' soldering-lamp, as will be hereinafter more fully set forth.

In order to enable others skilled in the art to which my invention appertains to make and use the same, I will now proceed to describe its construction and operation, referring to the annexed drawing, in which—

Figure 1 is a side elevation of my lamp. Fig. 2 is a plan view of the same with the lid thrown open, and Fig. 3 is an enlarged side view of one end of the lamp.

A represents the shell of the lamp, provided with a vertical partition, *a*, and a horizontal partition, *b*, near the top, as shown by dotted lines in Fig. 1. The chamber *B*, formed by the partitions *a* and *b*, and the corresponding portion of the shell *A*, constitutes the lamp proper, which is filled through the aperture *d*, shown in Fig. 2, while the chamber *C*, on the other side of the vertical partition *a*, is for the purpose of holding water or diluted acid. On top of the partition *b* are two other small partitions or flanges, *e f*, forming three spaces or apartments, one of which contains a slate, *D*, covering the orifice *d*, said slate being for the purpose of grinding borax. The other two apartments *E* are for the pur-

pose of holding solder, clamps, &c. At this end of the shell are formed lips *G*, constituting a convenient receptacle for the piece of borax when not in use. From the lamp *B* a tube, *H*, leads outward and upward, said tube containing a large wick, *g*, suitable for any work. On the end of the tube *H* is placed a cap, *I*, with a smaller tube at the end, through which is passed a smaller wick, *h*, to give a small blaze for light work. This is covered by another cap, *J*, as shown. The wick *h* in the cap *I* is fed by coming in contact with the large wick *g*. On the front of the shell *A* is a pocket, *H*, to contain matches. The entire shell is covered by the lid *L*, or I may make separate lids for the various compartments, or in some cases I may dispense with any lid for the whole or a part of the same. The additional cap *I*, with its wick *h* and cap *J*, may be applied to any soldering-lamp.

Having thus fully described my invention, what I claim as new, and desire to secure by Letters Patent, is—

1. The cap *I* with small wick *h*, to be used in combination with the usual wick and wick-tube of a soldering-lamp, substantially as and for the purposes herein set forth.
2. The shell *A*, partitions *a*, *b*, *e*, and *f*, chambers *B* *C*, slate *D*, lips *G*, pocket *K*, and tube *H*, with or without the lid *L*, all constructed and arranged substantially as shown and described, and for the purposes herein set forth.

In testimony that I claim the foregoing I have hereunto set my hand this 30th day of December, 1870.

WILLIAM H. TALLMAN.
